UNITED STATES PATENT OFFICE.

JOHN GILSON, OF PORT WASHINGTON, WISCONSIN.

GRINDING-MACHINE.

SPECIFICATION forming part of Letters Patent No. 701,031, dated May 27, 1902.

Application filed September 20, 1901. Serial No. 75,914. (No model.)

To all whom it may concern:

Be it known that I, JOHN GILSON, a citizen of the United States, and a resident of Port Washington, in the county of Ozaukee and State of Wisconsin, have invented certain new and useful Improvements in Grinding-Machines; and I do hereby declare that the following is a full, clear, and exact description thereof.

10 My invention has for its object to improve the detail of that species of grinding-machines set forth in Patent No. 655,753, of August 14, 1900, as especially designed for agriculturists, said invention consisting in what is hereinafter particularly specified with reference to the accompanying drawings and subsequently claimed.

Figure 1 of the drawings represents an elevation of the improved machine, partly in section, lengthwise thereof; Fig. 2, a plan view of a portion of the machine-base and vertically-adjustable incline-plane brackets therewith, these brackets being a feature of the improvements; Fig. 3, a detail sectional elevation illustrating one of said brackets in connection with the base and supporting the reciprocative grinding-device carrier of the machine; Fig. 4, a detail partly-sectional view indicated by line 4-4 in the first figure; and Fig. 5, a detail perspective view illustrating the lower portion of a carrier-support having detachable connection with said base, this support and a base-rib engageable therewith being another feature of the improvements.

35 Referring by letter to the drawings, A indicates the cast-metal base of the improved machine, provided with the usual lugs b and rests c thereon for abutment of a sickle-bar and knife-sections of the same, this base, standard-yoke B, rocker-yoke C, grinding-device carrier D, clamp-jaw E, and means for tightening said jaw being similar in general construction and arrangement to like parts set forth in the aforesaid patent, any 40 improvements being means for automatic lift of said carrier at the finish of stroke in either direction of its reciprocation and for holding the aforesaid carrier in stationary elevated position when desirable.

50 In accordance with my improvements the base A is provided with a pair of parallel vertically-slotted and flanged standards F, that

constitute guides for depending apertured shanks d of converging incline planes G, bolts e engaging the standard-slots, shank-aper- 55 tures, and nuts f to hold the brackets comprising said planes and their shanks in vertically-adjusted position. The incline-plane brackets are in the path of a journal-bearing g, constituting part of carrier D, when the machine is being used for grinding knife-sections of sickle-bars, the grinding device H being best shown in Fig 3. By means of the incline-plane brackets the carrier and grinding device H therewith are automatically lifted at 65 the finish of stroke on the part of said carrier in either direction of its reciprocation, whereby overgrinding of the sickle-bar knife-sections is prevented, independent vertical adjustment of said brackets being in proportion 70 to the length of said knife-sections.

At the side of the machine farthest from standards F and on a line between these standards the base A is provided with an upright transverse rib I, the upper outer end of which 75 is vertically extended in the form of a lug h, and this rib is designed to fit a vertical center recess in the lower end of a support J, that of itself is provided with inner lower end lugs i, these lugs being caught under a lateral 80 flange j of said base when the support is placed on said rib, abutting the lug h of same. The upper portion of the support J is provided with a seat for a lateral stud k of the carrier D and is preferably made with an angular recess, whereby said support may have the function of a wrench when detached from the machine.

When positioned in connection with the base and grinding-device carrier of the machine, the support J serves to hold said carrier stationary at a suitable elevation clear of the sickle-bar clamp and converging inclined planes G whenever necessary or desirable—say, for instance, when said inclined 95 planes are being adjusted. However, the support herein set forth is novel only in the peculiar construction of its lower end and in combination with the rib I and flange j of the machine-base, said support being a detachable appendage of the machine held in working position independent of the clamp-jaw specified.

Having thus described my invention, what

I claim as new, and desire to secure by Letters Patent, is—

1. A grinding-machine of the species described having the clamp end of its base provided with an inclined plane in the path of the reciprocative grinding-device carrier of the machine.
2. A grinding-machine of the species described having the clamp end of its base provided with inclined planes arranged in the path of the reciprocative grinding-device carrier of the machine to automatically lift the same when on stroke in either direction of its travel.
- 15 3. A grinding-machine of the species described having the clamp end of its base provided with standards, and converging incline-plane brackets vertically adjustable on the standards in the path of a portion of the reciprocative grinding-device carrier of the machine.
- 25 4. A grinding-machine of the species described having the clamp end of its base provided with vertically-slotted and flanged standards, converging incline planes having depending apertured shanks engaging the standards, bolts extending through the standard-slots and shank-apertures, and nuts run on the bolts, said planes being in the path of
- 30 a portion of the reciprocative grinding-device carrier of the machine.
5. A grinding-machine of the species described having the clamp end of its base provided with a lateral flange and an upright

transverse rib the upper outer end of which 35 has the form of a vertical lug, and the grinding-device carrier of the machine provided with a lateral lug, the base-rib being for engagement with a lower end recess of a support engageable with the carrier-lug and of 40 itself provided with lugs that extend in under said flange, said support serving when in working position to temporarily hold the carrier and grinding device in stationary elevated position.

45 6. A grinding-machine of the species described provided with an attachment in the form of a support having an upper end seat for a lateral lug on the grinding-device carrier of the machine, a lower recess for the engagement of a base-rib of said machine inside an upper lug extension of the same, and lower end lugs that extend under a lateral base-flange of the aforesaid machine when said engagement is effected, said support in 50 working position serving to hold the carrier and grinding device of the machine in stationary elevated position.

In testimony that I claim the foregoing I have hereunto set my hand, at Port Washington, in the county of Ozaukee and State of Wisconsin, in the presence of two witnesses.

JOHN GILSON.
